BISCUIT BASKET FOR POP-UP TOASTERS

Harrison Keller, 456 W. Ohio Ave., Sebring, Ohio

Filed Dec. 4, 1964, Ser. No. 82,909

Term of patent 14 years

(Cl. D81—10)

The figure is a perspective view of a biscuit basket for pop-up toasters, showing my new design. The bottom, back edge and end of the handle not shown are substantially plain.

I claim:

The ornamental design for a biscuit basket for pop-up toasters, as shown and described.
